BY

UNITED STATES PATENT OFFICE.

JOSEPH FRIEDMAN, OF PHILADELPHIA, PENNSYLVANIA.

DESIGN FOR A DRAIN-PIPE.

44,609.

Specification for Design.

Patented Sept. 2, 1913.

Application filed June 3, 1912. Serial No. 701,460. Term of patent 7 years.

To all whom it may concern:

Be it known that I, JOSEPH FRIEDMAN, a citizen of the United States, residing at Philadelphia, in the county of Philadelphia and State of Pennsylvania, have invented a new, original, and ornamental Design for Drain-Pipes, of which the following is a specification, reference being had to the accompanying drawing, forming part thereof.

Figure 1, is a plan view of a drain pipe, showing my new design. Fig. 2, is a side view thereof.

Referring to the drawings, 2 designates a central, straight, vertical portion, 3 a straight horizontal portion on one side of the central portion, 4 a straight vertical portion on the other side of the central portion 2; the bottom of the central portion 2 and

the inner end of the portion 3 being connected by the ornamental ogee curved portion 5, and the bottom of the portion 4 and the body of the portion 2 being connected by the ornamental, combined inclined straight portion 6 and curved portion 7, the configuration of the resultant whole constituting my new design.

I claim:

The ornamental design for a drain pipe, as shown and described.

In testimony whereof I affix my signature in the presence of two witnesses.

JOSEPH FRIEDMAN.

Witnesses:

A. V. GROUPE,
G. P. SHARKEY.
